UNITED STATES PATENT OFFICE.

FREDRICK L. PETERSON, OF HELIX, OREGON.

BABBITTING-MACHINE FOR JOURNAL-BOXES.

1,196,143.

Specification of Letters Patent. Patented Aug. 29, 1916.

Application filed May 15, 1916. Serial No. 97,678.

To all whom it may concern:

Be it known that I, FREDRICK L. PETERSON, a citizen of the United States, residing at Helix, in the county of Umatilla and State of Oregon, have invented certain new and useful Improvements in Babbittting-Machines for Journal-Boxes, of which the following is a specification, reference being had to the accompanying drawings.

10 This invention relates to certain improvements in babbittting machines for journal boxes and it is an object of the invention to provide a device of this general character having novel and improved means whereby 15 the box to be babbitted may be effectively held in desired position, and whereby the same may be adjusted in accordance with the requirements of practice.

It is also an object of the invention to 20 provide a machine of this general character having novel and improved means wherein the shaft coacting with the box may be readily adjusted relative to the box in order to facilitate the application of the babbitt.

25 The invention consists in the details of construction and in the combination and arrangement of the several parts of my improved machine whereby certain important advantages are attained and the device is 30 rendered simpler, less expensive and otherwise more convenient and advantageous for use, all as will be hereinafter more fully set forth.

The novel features of the invention will 35 hereinafter be definitely claimed.

In order that my invention may be the better understood, I will now proceed to describe the same with reference to the accompanying drawings, wherein—

40 Figure 1 is a view in elevation illustrating a babbittting machine constructed in accordance with an embodiment of my invention, the coacting box and shaft being shown in applied position; Fig. 2 is a view in top plan with parts in section of my improved machine as herein embodied; Fig. 3 is a fragmentary longitudinal and horizontal sectional view taken through the intermediate portion of the machine as herein disclosed; Fig. 4 is a vertical sectional view taken through an end of the machine as

herein included; and Fig. 5 is a transverse vertical sectional view taken through the central portion of the machine as herein set forth, certain of the parts being omitted for clarity in disclosure.

As disclosed in the accompanying drawings, 1—1 denote side members of a frame F maintained in predetermined spaced relation by the transverse members 2. Substantially midway the length thereof, the side members 1 have rotatably engaged therewith the transversely disposed rod 3 provided at its opposite end portions with the reversely directed threads 4 and at one end 65 with an operating member 5 whereby the requisite rotation may be imparted to the rod 3.

6 and 7 denote clamping members adapted to engage and hold a journal box B to be 70 babbitted, said box B being of a conventional type, and as herein disclosed, the member 6 is of a length greater than the member 7 and has secured to the opposite end portions thereof the upstanding goose-necks 8 formed at the adjacent ends of the rods 9. The rods 9 are disposed transversely of the frame F and slidably engaged with the side members 1 and have their opposite end portions connected by the cross 75 head 10 with which the rod 3 is in threaded engagement. The second clamping member 7 is secured to the upstanding goose-necks 11 carried by the rods 12 also disposed transversely of the frame F and slidably engaged 80 with the members 1, the opposite end portions of said rods 12 being connected by the cross head 14 through which the rod 3 is also threaded, whereby it will be perceived that upon rotating the rod 3, the clamps 6 and 85 7 will be caused to move in unison but in opposite directions. The rods 12 are positioned intermediate the rods 9 and in order to prevent the cross head 10 from obstructing the movement of the rods 12, I find it of 90 advantage to provide the upper marginal portion of said cross head 10 with the recesses 15 through which the rods 12 and the upstanding goose-necks 11 are free to pass.

It is to be understood that the rod 3 is 100 incapable of longitudinal movement relative to the frame F and as herein disclosed, is

held against longitudinal movement by the collars 16 fixed to said rod 3 and disposed at opposite sides of the members 1.

The transverse members 2 are preferably arranged in pairs at the opposite ends of the members 1 and serve as guides for the heads 17 preferably two in number and having the upstanding bars 18 tied or connected at their upper ends by the cross heads 19.

10 Slidably engaged with each set of bars 18 are the clamping members 20 and 21 adapted to coact with the shaft S, and the lower member 20 has its opposite extremities engaged with the threaded rods 22 loosely disposed through the cross head 19 and in threaded engagement with the upper clamping member 21, whereby it will be perceived that upon requisite axial rotation being imparted to the rods 22, the clamping members 20 and 21 may be relatively moved in order to effect the requisite clamping engagement with a shaft S or to disengage the same therefrom. The upper end portions of the rods 22 are provided with the operating members 23.

15 Threaded through the cross head 19 and in swiveled engagement with the upper clamping member 21 is the rod 24 provided at its upper end with suitable means 25 for axially rotating the same. It will be perceived that upon requisite rotation of the rod 24, the clamping members 20 and 21 may be raised or lowered as desired, and whereby the shaft S may be adjusted relative to the box B.

20 Disposed transversely of the frame F and rotatably supported by the members 1 at points intermediate the members 2 at each end of the frame, is the rod 26 provided at one end with an operating member 27, said rod 26 being in threaded engagement with the heads 17 whereby it will be perceived that upon requisite rotation of the rod 26, the clamping members 20 and 21 may be adjusted transversely of the frame F.

25 From the foregoing description, it is thought to be obvious that a machine constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice.

I claim:

1. A device of the character described comprising a frame, box clamps adjustably

carried by the frame and movable transversely thereof, means for moving said clamps in unison but in reverse directions, and shaft engaging members carried by the frame.

2. A device of the character described comprising a frame, box clamps adjustably carried by the frame and movable transversely thereof, means for moving said clamps in unison but in reverse directions, shaft engaging members carried by the frame, and means for adjusting the shaft engaging members transversely of the frame.

3. A device of the character described comprising a frame, box clamps adjustably carried by the frame and movable transversely thereof, means for moving said clamps in unison but in reverse directions, shaft engaging members carried by the frame, and means for adjusting said shaft engaging members in a vertical path.

4. A device of the character described including a frame, box clamps, rods slidably disposed transversely of the frame and provided with upstanding goose-necks secured to the clamps, cross heads connecting adjacent ends of the rods, and means carried by the frame common to the cross heads for imparting movement to the clamps in unison but in reverse directions.

5. A device of the character described comprising a frame, box engaging means carried thereby, shaft engaging members carried by the frame, said shaft engaging members each including heads mounted for sliding movement transversely of the frame, and a shaft clamping member carried by the head.

6. A device of the character described comprising a frame, box engaging means carried thereby, shaft engaging members carried by the frame, said shaft engaging members each including heads mounted for sliding movement transversely of the frame, upstanding rods carried by the heads, clamping members slidably engaged with the rods, a cross head connecting the rods, and means for imparting relative movement to the clamping members.

7. A device of the character described comprising a frame, box engaging means carried thereby, shaft engaging members carried by the frame, said shaft engaging members each including heads mounted for sliding movement transversely of the frame, upstanding rods carried by the heads, clamping members slidably engaged with the rods, a cross head connecting the rods, means for imparting relative movement to the clamping members, and means carried by the cross head coacting with one of the clamping members for imparting movement to said clamping members in a direction toward or from the frame.

8. A device of the character described comprising a frame, box clamps carried by the frame, shaft engaging members carried by the frame, and means for adjusting the 5 shaft engaging members transversely of the frame.

9. A device of the character described comprising a frame, box clamps carried by the frame, shaft engaging members carried

by the frame, and means for adjusting said 10 shaft engaging members in a vertical path.

In testimony whereof I hereunto affix my signature in the presence of two witnesses.

FRED L. PETERSON.
